ESCUTCHEON PLATE

Van Day Truex, New York, N. Y., assignor to The Yale & Towne Manufacturing Company, Stamford, Conn., a corporation of Connecticut

Application May 4, 1956, Serial No. 41,340

Term of patent 7 years

(Cl. D50—6)

Fig. 1 is a front elevational view of an escutcheon plate showing my new design.

Fig. 2 is a side view as viewed from the left of Fig. 1.

Fig. 3 is a bottom end view of the escutcheon plate.

Fig. 4 is a cross-section on the line 4—4 of Fig. 1.

I claim:

The ornamental design for an escutcheon plate, substantially as shown.
